UNITED STATES PATENT OFFICE.

JUSTUS R. KINNEY, OF DORCHESTER, MASSACHUSETTS, ASSIGNOR TO THE KINNEY MANUFACTURING COMPANY, OF BOSTON, MASSACHUSETTS, A CORPORATION OF MASSACHUSETTS.

ROTARY PUMP.

1,137,215.

Specification of Letters Patent.

Patented Apr. 27, 1915.

Application filed March 4, 1914. Serial No. 822,539.

To all whom it may concern:

Be it known that I, JUSTUS R. KINNEY, a citizen of the United States of America, and a resident of Dorchester, in the county of 5 Suffolk and State of Massachusetts, have invented certain new and useful Improvements in Rotary Pumps, of which the following is a specification.

This invention relates to rotary pumps, 10 and has for its object the production of a pump which will be simple in construction and very effective in operation, and in which the annular piston will be supported upon a film of liquid under pressure interposed between its inner cylindrical wall and the 15 periphery of its operating eccentric.

The invention consists in providing the inner cylindrical wall of the annular piston with a transverse groove communicating by 20 a passage with the outlet compartment whereby the liquid being pumped may enter between the periphery of the eccentric and the cylindrical inner wall of the annular piston and support the latter during the 25 operation of the pump, thus providing a means whereby the liquid thus entering between said eccentric and piston will be maintained at a constant pressure.

The invention further consists in certain 30 novel features of construction and arrangement of parts which will be fully understood by reference to the description of the drawings and to the claims hereinafter given.

35 Of the drawings: Figure 1 represents a vertical section of a pump embodying the features of the present invention, the cutting plane being on line 1—1 on Fig. 2. Fig. 2 represents a transverse section of the 40 same, the cutting plane being on line 2—2 on Fig. 1, and Fig. 3 represents a view of a portion of the inner wall of said annular piston.

Similar characters designate like parts 45 throughout the several figures of the drawings.

In the drawings, 10 represents a casing supported by the feet 11 and having a cylindrical piston chamber 12 and the inlet and 50 outlet compartments 13 and 14 respectively.

A passage 15 forms a means of communication between the inlet compartment 13 and the piston chamber 12, while a passage 16 forms a means of communication between

the piston chamber and the outlet compartment. 55

Extending through the piston chamber 12 is a shaft 17 revoluble in bearings 18 on the casing 10 and in the end plate 19 secured to said casing 10. The shaft 17 has secured 60 thereto within the piston chamber 12 an eccentric 20.

The eccentric 20 is keyed to the shaft 17 and revolves therewith. Upon the eccentric is mounted an annular piston member 21 65 which is adapted to always contact at one point in its periphery with the cylindrical wall of said piston chamber during the rotation of the shaft 17.

In the outlet passage 16 is a cylindrical 70 recess 22 in which is positioned an oscillating cylinder 23 having a diametral slot 24 extending therethrough. A radial blade 25 rigidly secured to the annular piston 21 extends through the slot 24, this blade being 75 provided with a depression 26 in one face thereof through which the material being pumped is adapted to be discharged into the outlet compartment 14. An outlet pipe 27 communicates with the compartment 14 and 80 material is admitted to the compartment 13 through the inlet pipe 28. The blade 25 accurately fits the slot 24 and is adapted to reciprocate therein and as the material being pumped is discharged through the de- 85 pression 26 the blade 25 is forced against the opposite wall, thus effectually preventing leakage from the outlet side of the pump into the inlet compartment 13. By discharging the material through the de- 90 pression 26 in the blade 25 the construction of the pump is greatly simplified by dispensing with a separate discharge outlet while at the same time means is provided whereby the blade in its reciprocation is 95 thoroughly lubricated by the material being pumped. Moreover, by this construction there is no opportunity for the material to become pocketed. The inner cylindrical wall of the annular piston 21 is provided 100 with a groove 29 which terminates within the side walls of said annular piston 21 as indicated in Fig. 3 of the drawings. From the groove 29 a radial hole or passage 30 extends to the depression 26 of said piston 105 blade, thereby communicating with the outlet compartment 14, so that as the material is being pumped by the revolution of the

piston portions thereof will be forced under constant pressure through the passage 30 into the groove 29, effecting a thorough lubrication of the inner wall of the annular member 25 as the eccentric 20 revolves therein.

By having the space 31 between the periphery of the eccentric 20 and the annular member 21 connected by the passage 30, the fluid under constant pressure in the outlet compartment 14 is permitted to enter this space 31 when the pump is in operation and support the said annular member 21 on a thin film of said fluid throughout the cycle of said eccentric 20 within said annular member. As a consequence of this construction with the film of fluid under constant pressure over the entire periphery of the eccentric 20 the annular member is supported on a hydraulic cushion and retained at all times concentric with the axis of said eccentric, and the adjacent surfaces are prevented from coming into frictional contact and becoming worn. This is of great importance, for otherwise the annular member and the eccentric become worn unevenly and result in an imperfect operation of the pump. Constructed as herein shown and described, the eccentric will rotate within the annular member for an indefinite period without any appreciable wear.

It is believed that the operation and many advantages of the invention will be fully understood from the foregoing description.

Having thus described my invention, I claim:

1. In a device of the class described, the combination of a casing provided with a cylindrical piston chamber and an outlet compartment communicating therewith; a revolute shaft centrally disposed therein; an eccentric thereon; and an annular piston on said eccentric having a radial blade extending into said outlet compartment and provided with a groove extending transversely of its inner cylindrical wall communicating with the outlet compartment by means of a passage through said blade.

2. In a device of the class described, the combination of a casing provided with a cylindrical piston chamber and an outlet compartment communicating therewith; a revolute shaft centrally disposed therein; an eccentric thereon; and an annular piston on said eccentric having a radial blade extending into said outlet compartment and provided with a groove extending transversely of its inner cylindrical wall communicating constantly with the outlet compartment by means of a passage through said blade.

3. In a device of the class described, the combination of a casing provided with a cy-

lindrical piston chamber and an outlet compartment communicating therewith; a revolute shaft centrally disposed therein; an eccentric thereon; and an annular piston on said eccentric having a radial blade extending into said outlet compartment and provided with a groove extending transversely of its inner cylindrical wall communicating constantly with the outlet compartment.

4. In a device of the class described having an inclosed outlet compartment, the combination of an eccentric, an annular piston, and means for supplying a film of liquid between said eccentric and piston under constant pressure through a passage communicating directly with said outlet compartment.

5. In a device of the class described having an outlet compartment, the combination of an eccentric, an annular piston, and means for supplying directly from said outlet compartment a film of liquid between said eccentric and piston under constant pressure.

6. In a device of the class described, the combination of a casing provided with a cylindrical piston chamber, an inlet passage thereto, an outlet compartment, and a smaller cylindrical recess communicating with said piston chamber; a cylindrical oscillating member positioned in said recess provided with a transverse slot; a revolute shaft centrally disposed in said piston chamber; an eccentric thereon; and an annular piston on said eccentric having a radial blade extending through the slot in said oscillating member, and provided with a passage from its inner annular wall extending through said blade and communicating with said outlet compartment.

7. In a device of the class described, the combination of a casing provided with a cylindrical piston chamber, an inlet passage thereto, an outlet compartment, and a smaller cylindrical recess communicating with said piston chamber; a cylindrical oscillating member positioned in said recess provided with a transverse slot; a revolute shaft centrally disposed in said piston chamber, an eccentric thereon; and an annular piston on said eccentric having a radial blade extending through the slot in said oscillating member, and provided with a depression in its outlet side and having a passage from its inner annular wall extending through said blade and communicating with said depression.

Signed by me at Boston, Mass., this 19th day of February, 1914.

JUSTUS R. KINNEY.
